UNITED STATES PATENT OFFICE.

ALBERT A. SNEBOLD, OF NATRONA, PENNSYLVANIA.

PLUMB-BOB.

SPECIFICATION forming part of Letters Patent No. 632,286, dated September 5, 1899.

Application filed March 27, 1899. Serial No. 710,606. (No model.)

To all whom it may concern:

Be it known that I, ALBERT A. SNEBOLD, a citizen of the United States of America, residing at Natrona, in the county of Allegheny and State of Pennsylvania, have invented certain new and useful Improvements in Plumb-Bobs; and I do hereby declare the following to be a full, clear, and exact description thereof, reference being had to the accompanying drawings, which form a part of this specification.

My invention relates to an improved plumb-bob; and it consists in a device whereby the cord used for suspending the said plumb-bob may be reeled and kept within the same, together with certain details of construction and combination of parts, as will be fully described hereinafter.

In the accompanying drawings, Figure 1 is a side elevation of my improved plumb-bob. Fig. 2 is a similar view, partly shown in section, the better to show the internal parts, consisting of the reel for winding the cord suspending the plumb-bob. Fig. 3 is a plan view of the same. Fig. 4 is a plan view of my improved plumb-bob having the upper portion removed therefrom.

To put my invention into practice with an ordinary plumb-bob constructed and formed in a manner well known in the art, and consisting of a steel tapering or conical point 1 and a corresponding body portion, this body is divided into an upper section 5 and lower section 2, the one joined to the other by means of a screw-thread 3, formed upon an upwardly-projecting annular collar or sleeve 4, integral with the body portion 2, the construction and form of which leaves a circular space 6, in which a reel 7 is placed, the journals 7' of which are journaled in the aforesaid sleeve 4. Intermediate of the said upper section 5 and lower section 2 of the plumb-bob is a collar 8, having a serrated periphery, by means of which the said collar may be easily revolved by the operator.

Forming a part of the above-described collar 8 and arranged about its upper periphery is a ratchet or gear 9, which engages with a small gear or bevel pinion 10, mounted upon one end of the shaft carrying the reel 7. Attached to this reel 7 is a cord 11, the other extremity of which projects through a tension-cap at the top of the plumb-bob, and the said cord 11 and an attached ring 12 used in a manner well known in the practical use of 55 the plumb-bob. This tension device consists of a threaded cap 13, bearing upon a divided gland 14 in a manner that when the said cap 13 is screwed downward the gland will bind itself about the cord 11 and prevent the same from moving, or if the said gland is released the cord will have a free passage through the ports.

In operation the cord 11 may be withdrawn to its full extent, but may be stopped at any 65 point by screwing down the cap 13 (thereby tightening the glands 14) and stopping the cord at any point desired. The cord may be rewound about the reel 7 by simply turning the serrated collar 8 in the proper direction, 70 which movement will operate the pinion 10 and reel 7 to wind or reel the cord 11.

Having thus described my invention, I claim.

A plumb-bob consisting of the upper and 75 lower section, the one separated from the other by a serrated collar 8, a reel 7, arranged intermediate of the two sections operated by the said collar and a locking device, substantially as described for confining the plumb- 80 cord at any desired position as described.

In testimony whereof I have hereunto affixed my signature in the presence of two subscribing witnesses.

ALBERT A. SNEBOLD.

Witnesses:

JOHN GROETZINGER,
H. E. BECKER.
